US00D800651S

(12) **United States Design Patent** (10) **Patent No.:** **US D800,651 S**
(45) **Date of Patent:** **** Oct. 24, 2017**

(54) **CHARGER**

(71) Applicant: **ZAPGOCHARGER LTD**, Didcot (GB)

(72) Inventors: **Stephen Voller**, Didcot (GB); **Jonathan Tuck**, Didcot (GB); **Marappa Rajendran**, Didcot (GB); **Tim Walder**, Didcot (GB)

(73) Assignee: **ZapGo Ltd.**, Didcot (GB)

(**) Term: **15 Years**

(21) Appl. No.: **35/500,795**

(22) Filed: **Oct. 2, 2015**

(80) **Hague Agreement Data**

Int. Filing Date: **Oct. 2, 2015**

Int. Reg. No.: **DM/089264**

Int. Reg. Date: **Oct. 2, 2015**

Int. Reg. Pub. Date: **Apr. 8, 2016**

(51) **LOC (10) Cl.** 13-03

(52) **U.S. Cl.**

USPC **D13/103**

(58) **Field of Classification Search**

USPC D13/107, 108, 102, 110, 103

See application file for complete search history.
